DESCRIPTION

FIG. 1 is a left perspective view of a photo booth in accordance of the present invention;

FIG. 2 is a left side elevation view thereof;

FIG. 3 is a right side elevation view thereof;

FIG. 4 is a rear elevation view thereof;

FIG. 5 is a front elevation view thereof;

FIG. 6 is a top plan view thereof; and,

FIG. 7 is a bottom plan view thereof.

The broken lines immediately adjacent the shaded areas represent the bounds of the claimed design while other broken lines are directed to environment and are for illustrative purposes only; features illustrated in broken lines form no part of the claimed design.
